SWITCH ACTUATING MECHANISM

Eric Axel Ericson, Plainville, Conn., assignor to
 The Trumbull Electric Manufacturing Company,
 Plainville, Conn., a corporation of Connecticut

Application December 27, 1945, Serial No. 637,349

8 Claims. (Cl. 74—100)

1

My invention relates particularly to mechanism for actuating electric switches.

The main object is to provide simple but effective mechanism which can be applied to the outside of switch boxes for actuating the mechanism inside.

A special object is to provide snap action or quick make and quick break mechanism capable of being embodied in various forms of switches.

Fig. 1 is a face view of one form of device embodying my invention, the moving parts being shown in full lines in one extreme position and in dot-dash lines in the other extreme position, such positions for instance as represent the "on" and "off" positions of an electric switch.

Fig. 2 is a sectional view on the plane of the line 2—2 of Fig. 1.

Fig. 3 is a fragmentary section on the plane of the line 3—3 of Fig. 4.

Fig. 4 is a face view of the stationary parts of the device, parts being broken away.

Fig. 5 is a face view of the hub of the handle member.

The device is adapted to be secured to the front or side wall of a switch box depending upon the particular form of switch mechanism (not shown). In this case 7 indicates a fragment of the switch box wall.

The attachment has a base plate 8 which may be attached to the wall 7 in any suitable manner, for instance by screws, bolts or welding at 9, 9. Mounted on this base 8 are two U-shaped track members 10 and 11. These are secured together and to the base plate 8 by rivets 12, 13 and 13 and properly spaced by collars. The ends of the upper track member extend beyond the lower track member and are secured to the base plate by rivets 14, 14. These parts 8, 10, 11, 12, 13 and 14 constitute the guide frame for the handle.

The handle member 15 has a cylindrical hub 16 rotatably mounted about the base plate 8 and the outer edges of the track members 10 and 11. A fragment of an annulus 17 is interposed between the track member 10 and the base 8 and is secured to the hub 16 for instance by screws 18.

The throwing device is mounted within the handle member and its hub and extends into the U-shaped track members. A rod 20 has a pair of rollers 21, 22 mounted on a pin 23 which extends through the rod, through the slot 24 in the base plate and into the switch box where it engages the movable switch member (not shown). The other end of the rod 20 is slotted and is slidably guided by the cross pin 25 in the handle.

A spring 26 is mounted on the rod 20 between

2

the abutment 27 of the rod and the cross pin 25 in the handle so as to press the rollers 21, 22 against the inner edges of the track members 10 and 11. An auxiliary reinforcing member 28 is secured to the rod 20 by rivets 29 and constitutes with it the throwing arm. The studs 14, 14 constitute fulcrum points for the throwing arm. The side edges 30, 30 of the track member constitute stops for the rollers 21, 22. The bottom edges 31, 31 extend in a direction generally transverse to the mid position of the handle and constitute supporting tracks for the rollers as they move between the stops. The central part of each edge 31 is substantially straight so as to afford a minimum resistance to movement of the rollers as they move from one side to the other of the track members.

When the handle is moved from the full line to the dot-dash line position of Fig. 1 its hub 16 turns about the base plate 8 and the track members 10 and 11. As the pin 25 swings on an arc about the center of the hub the spring 26 is compressed until the part 28 of the throwing arm strikes the stud 14. Continued movement of the handle turns the arm about one stud 14 as a pivot until the power of the spring throws the rollers 21, 22 and the pin 23 from the lower to the upper position of Fig. 1, the rollers traveling along the tracks at the bottom of the U-shaped track members until they strike against the upper edge 30 and the auxiliary bar strikes the lower stud 14. When the handle is moved back toward its upper position the reverse action takes place and the spring throws the handle and the pin back to their full line positions where the rollers 21, 22 press against the lower side edges 30, 30 of the track member and the member 28 of the throwing arm 20 engages the upper stud 14.

It will thus be seen that the movement is very quick in either position.

I claim:

1. Snap action mechanism comprising a guide frame having a slotted base plate and a plate with a circular outer rim and a transverse inner track, a handle having a hub mounted to oscillate on said frame, a throwing arm having a roller at one end guided on said track and slidable in the handle, a compression spring mounted on said arm for throwing said arm and a pin carried by said arm and projecting through said base plate.

2. Snap action mechanism comprising a guide frame having a U-shaped plate with a circular outer rim and a transverse inner track, a handle having a cylindrical hub mounted to oscillate on

55

said frame, a throwing arm having a roller at one end guided on said track and slidably engaging an abutment in the handle and a compression spring mounted on said arm between said abutment and said roller.

3. Snap action mechanism comprising a guide frame having a circular outer rim and a transverse inner track, a handle having a cylindrical hub mounted to oscillate on said frame, a throwing arm having a roller at one end guided on said track and slidably engaging a cross pin in the handle, a compression spring mounted on said arm and abutments on said frame serving as pivots about which said arm turns when said handle is turned.

4. Snap action mechanism comprising a guide frame consisting of a base plate and two U-shaped track plates held spaced apart by studs, each track plate having a circular outer rim and a transverse inner track, a handle having a hub mounted to oscillate on said frame, a throwing arm having rollers at one end guided on said tracks and slideable in the handle and a compression spring mounted on said arm for pressing said rollers against said tracks.

5. Switch actuating mechanism comprising a handle, means for pivoting said handle to permit it to be oscillated, a track extending substantially transverse to the mid position of said handle and having stop shoulders at its opposite ends, a roller mounted to travel along said track, a throwing rod connected at one end to said roller and having at its other end a sliding and swinging connection with the outer end of said handle, a spring on said rod for pressing said roller against said track and abutments adjacent the stop shoulders of said track engaged by said throwing rod for tilting said rod when the handle is swung about its pivotal means.

6. Snap action mechanism comprising a guide

frame consisting of a base plate and upper and lower U-shaped track plates held spaced apart by studs, each track plate having a circular outer rim and a transverse inner track, a handle having a hub mounted to oscillate on said frame, a throwing arm having rollers at one end guided on said tracks and slideable in the handle and a compression spring mounted on said arm for pressing said rollers against said tracks and a fragment of an annular member interposed between the base plate and the lower U-shaped track and secured to the hub for holding the parts on the base plate.

7. Snap action mechanism comprising a guide frame having a circular outer rim and a transverse inner track, a handle having a cylindrical hub mounted to oscillate on said frame, a throwing arm having a roller at one end guided on said track and slidably engaging a cross pin in the handle, abutments on said frame serving as pivots about which said arm turns when the handle is turned and a spring encircling said arm for pressing the roller against the track and for accelerating the pivotal movement of said arm.

8. Snap action mechanism comprising a guide frame having a slotted base plate, another plate with a circular outer rim and a transverse inner track, a handle having a cylindrical hub mounted to oscillate on said frame, a throwing arm having a roller at one end guided on said track and slidably engaging a cross pin in the handle, abutments on said frame serving as pivots about which said arm turns when the handle is turned, a spring encircling said arm for pressing the roller against the track and for accelerating the pivotal movement of said arm and a pin carried by said arm and projecting through said slotted base plate.

ERIC AXEL ERICSON.
